J. LA BARRE.
MULTIROUTE RAILWAY TICKET.
APPLICATION FILED SEPT. 9, 1913.

Patented Feb. 29, 1916.

UNITED STATES PATENT OFFICE.

JUDSON LA BARRE, OF CHICAGO, ILLINOIS.

MULTIROUTE RAILWAY-TICKET.

1,173,197.

Specification of Letters Patent. Patented Feb. 29, 1916.

Application filed September 9, 1913. Serial No. 788,803.

To all whom it may concern:

Be it known that I, JUDSON LA BARRE, a citizen of the United States, and a resident of Chicago, county of Cook, and State of Illinois, have invented certain new and useful Improvements in Multiroute Railway-Tickets, of which the following is a full, clear, and exact description.

The invention relates to multi-route coupon tickets for transportation over an initial line of road and other lines connecting therewith at different junction points, and seeks to provide a simple improved form in which the different details can be easily and quickly indicated and read.

The invention consists in the features of novelty hereinafter set forth, illustrated in the preferred form in the accompanying drawing and more particularly pointed out in the appended claims.

The drawing shows one form of the present improved ticket and comprises an agent's stub, a plurality of passage coupons and a contract portion. The different parts 25 or sections of the ticket are arranged horizontally from left to right lengthwise of the ticket, beginning with the agent's stub which is followed by the passage coupons arranged in the sequential order of their use 30 and ending with the contract portion at the right. Two or more passage coupons are employed in accordance with the different requirements. In the particular form shown two passage coupons are used, one for transportation over the initial line and one for transportation over the connecting line.

The agent's stub and each of the passage coupons is provided with a list of different routes, each route consisting of a junction 40 on the initial line and a railroad or line connecting with the initial line at such junction. For example, in the form shown, the list comprises eight different junctions which are assumed to be located upon the 45 Interline Railway and the names of the connecting lines are associated with the respective junctions. The names of the junctions and connecting lines are arranged upon the agent's stub and in each of the 50 passage coupons in a vertical column and preferably, as shown, the different routes are consecutively numbered. Each of these columns is also provided with a corresponding vertical column or row of stars or like 55 punch guides. As indicated in the drawing, the numbers and the punch guides are

arranged along the right hand margin of the agent's stub and alternately along the left and right hand margins of the succeeding passage coupons. Preferably, also, as 60 shown, when the ticket contains an even number of coupons, a similar row of stars or punch guides are located along the left hand margin of the contract portion.

Each of the sections of the ticket, including the agent's stub and the contract portion, is provided with a properly designated space *a* at the bottom of the list of routes for the destination. In the particular form shown, the destination is adapted to be written in the space with pen and ink. Below this space, each section of the ticket is provided with properly designated spaces *b* and *c* for indicating "half" and "2d class", and also with a space *d* marked "B. C." for 70 punching the ticket to cancel the same for baggage. The indicating spaces *b*, *c* and *d* are preferably arranged as shown below and in line with the columns of stars or punch guides opposite the list of routes. 75 Each section of the ticket is also provided with the form number and with a space *e* for the ticket number. The agent's stub and the passage coupons are provided at the extreme bottom portions with the name 80 of the issuing line and which name is also inserted at the top of the contract portion. The passage coupons are also preferably provided with properly designated spaces *f* to receive the punch marks of the different 85 conductors. The contract portion is provided at its right hand edge with the usual date staff *g* for indicating the limit of the 90 ticket.

The passage coupons are provided with 95 different captions which extend across the top of the ticket where they readily catch the eye. These captions are preferably emphasized by printing the same in heavy, bold faced type. These captions indicate 100 the different portions of the journey for which the respective coupons are good. Thus, for example, the first passage coupon contains the name of the issuing or initial line and indicates that the coupon is good 105 from the station on the initial line stamped on its back to the junction point indicated by a punch mark. The caption of the second coupon indicates that it is valid from the junction and over the line indicated by 110 the punch mark to the destination written in the space *a*.

The agent's stub and the coupon sections are separated by weakened vertical lines *h* and the last passage coupon on the contract portion is separated by a vertical line *j*, but which is preferably not a weakened line. When the ticket is to be executed or issued, it is folded upon the lines *h* and *j* beginning at the left. The first passage coupon is folded beneath the agent's stub and the succeeding coupons are each folded beneath the preceding one. The columns of stars or punch guides and the indicating spaces *b*, *c* and *d* will all register along the right hand margin of the agent's stub, so that the route and other details, as necessary, can be readily indicated by means of an ordinary single die punch. The instructions for issuing the ticket are preferably printed at the left hand part of the agent's stub and this printed matter is vertically disposed, so that it can be easily read by the agent in issuing the ticket. The agent's stub is also preferably provided at its upper portion with designated spaces *L* and *M* for indicating the route number for which the ticket is issued and the amount of the fare.

The improved ticket can be readily used for passage from any station on the initial line to any one of the junctions thereon and thence over the connecting line leading from such junction to the destination on such connecting line. In this way a single form may be used from the stations on one line to the destinations on any one of a number of lines connecting with the initial lines at different junctions. The ticket is easily issued or executed and is easily understood and read when issued. Furthermore, a complete record of the details of the ticket is provided upon the agent's stub and also upon each of the coupons.

It is obvious that changes may be made without departure from the essentials of the invention as defined in the claims.

45 I claim as my invention:—

1. A multi-route ticket for transportation over an initial line and a number of connecting lines comprising an agent's stub and two passage coupons connected in horizontal alinement from left to right lengthwise of the ticket and in geographical order of use, the said stub and each of said passage coupons having a list of junctions along the initial line, the name of each junction being associated with the name of the line connecting therewith, the list of junctions and the list of connecting lines being ar-

ranged in separate vertical columns and alternately disposed on said passage coupons adjacent the left and right hand margins thereof, said agent's stub and said coupons having corresponding vertical columns of consecutive numbers designating the separate junctions of the list and an associated vertical column of punch indications, said column of numbers and punch indications being alternately arranged at the right and left hand margins of the coupons and adapted to register along one margin when the ticket is folded, and said coupons having separate captions arranged in separate columns across the top of the ticket and indicating, by reference to the lists thereon, the portions of the journey for which the respective coupons are valid and said agent's stub and said passage coupons bearing the same form number and a suitably designated space for the name of the destination, substantially as described.

2. A multi-route ticket for transportation over an initial line and a number of connecting lines, comprising an agent's stub, and two coupons good for passage to and from a number of junctions along the initial line, said passage coupons being connected together in geographical order of use, said agent's stub and each of said passage coupons bearing a list of the junctions along the initial line and the name of each junction being associated with the name of the line connecting therewith, said lists of junctions and of connecting lines being arranged in separate vertical columns on said agent's stub and said passage coupons and being associated with vertical columns of punch indications and of consecutive numbers for designating the separate junctions of the list, said vertical columns of punch indications being arranged to register along one margin of said agent's stub when the ticket is folded beneath the same, said agent's stub and each of said coupons bearing the same form number and the name of the issuing line and a suitably designated space for the name of the destination, and each of said coupons having a different caption indicating by reference to the list of junctions and lines thereon the portion of the journey for which the particular coupon is valid, substantially as described.
